UNITED STATES PATENT OFFICE

HAROLD PITMAN SCHUCK, OF SAN FRANCISCO, CALIFORNIA

BOX-END-MAKING MACHINE

Application filed March 7, 1930. Serial No. 434,066.

This invention relates to composite-panel-making machines of the character set forth in my co-pending application Serial No. 337,441 filed February 4, 1929, for box-end making machines and aims to provide further improvements whereby a plurality of cleats may be applied simultaneously to grooved sections to form two or more in one panel and so double or still higher increase 10 the gross output capacity of the machine.

The invention will be best understood by description with reference to the attached drawings wherein one practicable embodiment is illustrated in a machine of construction similar to that shown in the aforesaid co-pending application.

In said drawings:

Fig. 1 is a plan view of the machine with parts particularly appertaining to the present 20 invention drawn in heavy lines;

Fig. 2 is a rear-end elevation of the machine on enlarged scale;

Figs. 3 and 3^a are enlarged longitudinal sections respectively of the forward and rearward halves of the machine drawn to the same scale for placing together to show a complete section; and

Fig. 4 is a front-end section of the machine on enlarged scale and omitting details of 30 construction not directly concerned with this invention.

The illustrative machine like that of the co-pending application is adapted to make composite box-ends or panels from lumber 35 of odd lengths and widths. By easy re-adjustment and change of certain parts, it is adapted also to make parquet floor sections and the like. It may facilitate understanding to here state that the machine assembles 40 a number of wooden slats or pieces side-by-side and then unites them in a rigid panel by first trimming and grooving their ends and thereafter forcing glue-coated cleats into the ends. Scrap-lumber from saw-mills may 45 advantageously be used for the purpose at much saving in material and expense.

Like the machine of said co-pending application, the instant one has a work-table formed by complementary slab sections 50 supported on side pedestals 6 providing a

strong and heavy structure (see Figs. 3 and 3^a). On a rear-corner of this table is a hopper comprising a bottom 7, a front-plate 8 with discharge opening 8^a and side-plates 9 and 10. One of the side-plates is shown laterally movable by a bar 11 extending through clamp-bracket 12 for altering the hopper width. A combined back-wall, assembly-platform and guide is provided by an inverted U-plate 13 supported on brackets 14 for slide movement toward and from the front-plate (see Figs. 1 and 2).

Into said hopper the odd lengths of lumber are piled in tiers of several lying side-by-side in parallel relation to the rear edge of the table. The number of slats in each tier will of course depend on their widths and the side-plate adjustment of the hopper, and they may vary somewhat in length to a maximum for which the back-plate 13 is set. An attendant supplying the hopper will find it convenient to arrange the "slats" in tiers on the top of the back-plate from which he may easily shove them into the hopper.

Under the hopper is a conveyor, which in 75 this instance comprises a pair of endless chains 15 running in grooves in the bottom or table and carrying one or more cross-bars 16. These chains pass around pairs of sprockets 17 and 18 keyed respectively on 80 shafts 19 and 20 and driven by power applied as later described.

The cross-bar (or bars) of this conveyor engages successively behind the ends of the lowermost tier of slats in the hopper and pushes 85 them forward through the discharge opening 8^a to position overlying another conveyor, their outward movement being limited by an abutment piece 21 opposite said opening. By thus removing the slats longitudinally instead of laterally, the possibility of jamming against superposed tiers is eliminated.

The said another or second conveyor comprises a pair of endless chains 22 moving longitudinally of the table at substantially right angles to the first and carrying spaced abutments or cross-bars 23. These chains pass around pairs of sprockets 24 and 25 keyed respectively on shafts 26 and 27 and driven 95 by power applied to the last-mentioned shaft 100

through a chain or belt 28 from a speed reducer associated with a motor 29 (see Figs. 3 and 3^a).

It may here be stated that the drive imparted to shaft 26 is advantageously transmitted to the aforementioned shaft 20 by intermeshing beveled gears 30 and 31, so that the two conveyors will move synchronously (see Fig. 2).

10 The second conveyor runs between ledge-rails 32 extending in parallel relation longitudinally of the table and providing guides between which the slats delivered across the conveyor are moved laterally along the table. Between the conveyor chains, a sill-plate 33 extends level with the ledge-rails and therewith provides grooves for the chains and also a slide-platform for the slats (see Figs. 1 and 2).

15 The abutments of this second conveyor successively engage behind the tiers of slats delivered successively thereover by the first conveyor and push them laterally along the slide-platform between the aforesaid ledge-rails to the forward end of table. During this movement and also during removal from the hopper, the slats are held down firmly by spring-tamps 34 shown arranged along bars 35 which are rigidly supported above and 20 between the ledge-rails by brackets 36 fixed on the latter (see Figs. 1, 2, 3 and 3^a).

25 The second conveyor successively engaging and carrying the slats along the table moves them initially against a pair of pivoted spring-tensioned levers 37 and 38 at one side of the slide-platform, which act on the ends of the slats with yielding pressure forcing their opposite ends to alignment against the shouldered rail or guide at the other side of 30 the platform (see Fig. 1).

35 Advancing continuously with the conveyor, the slats are next subjected to the action of a vertical saw 39 at the side of said levers, which trims the slats to equal lengths so that 40 their ends may align against the shouldered rail or guide at that side as well as the other side of the platform. Said saw is shown projecting through a slot in the ledge-rail and carried by the rotor-shaft of a motor 40 which is supported below the table top in a bed movable transversely thereof for a purpose later explained.

45 During said trimming operation, the slats are advantageously steadied by a spring-pressed roller 41 supported thereover adjacent the saw by a bracket 42 which is bolted to one of the elevated rods 35 (see Fig. 3^a).

50 On further advance, the slats are conveyed between horizontal saws 43 extending into 55 their path of movement so as to cut grooves in the edges at opposite ends thereof. These saws having dust-shields 44 are carried by the rotor-shafts of motors 45. Two saws are shown on each shaft for the purpose of cutting double grooves in both ends of the slats,

but obviously any number may be used according to the number of grooves desired to be cut. In cases where the slats are of greater than standard or usual thickness, it may be expedient to thus form three or more grooves in their ends. 70

75 Said motors for these grooving saws are shown supported under the table in carriages 46 which are mounted for vertical and horizontal movements, so as to bring the saws to desired elevation and spacing adjustment. This mounting is effected through bed-plates 47 in which said carriages are vertically slideable independently by actuation of screw-shafts 48 turned by hand wheels 49, while the bed-plates shown dove-tailed with a transverse part of the work-table are horizontally slideable, either independently or co-operatively in opposite directions. In this instance they are co-operatively slideable by 80 a connecting two-way worm-shaft 49 journaled in the table and operated as described later. 85

90 During the grooving operation, the slats are held down by spring-pressed shoes (not shown) supported by a bracket bolted to the elevated rods 35 as illustrated for example by the parts 50 and 51 in Fig. 3 of the aforesaid copending application.

95 After the trimming and grooving operations, the slats are delivered by the conveyor onto a portion of the slide-platform between opposing hoppers for the insertion of cleats or splines into their grooved ends.

100 In this delivery, the slats are impelled somewhat forwardly of a push-member 52 which normally projects above the platform surface, but yields against spring tension to permit the slats to ride thereover. This push-member thereupon engages behind the slats and moves them forward to exact position between the opposing hoppers against a stop-bar 53, which latter is simultaneously raised above the table top. Being thus positioned, the slats are then held under lateral compression between said push-member and stop-bar while the cleats are driven into their 105 grooved ends. 110

115 The push-member is mounted to tilt forwardly against spring tension in a block 54 which is slidably mounted on a pair of rods 55 extending rearwardly from a second block 56 and carrying springs 57 compressible behind the first-mentioned block for holding it normally abutting the second one. A buffer-block 58 is advantageously placed behind the two blocks. These blocks are countersunk in a longitudinal opening 59 in the table top and form part of a slide structure actuated intermittently to advance the push-member and simultaneously raise the stop-bar against the tiers of wooden pieces successively delivered between the cleat hoppers. 120

125 With said blocks, this slide structure comprises a frame of parallel bars 60 having 130

under-carriage connection with the block 56 and a supporting guide-block 61 which slides with the former on guide-rails 62 below the table top. Connected with the frame of bars 60 is shown a long rod 63 extending rearwardly thru a support-bracket 64 and carrying a recoil spring 65 between said bracket and a collar-member 63^a on its free end. This rod (hereinafter called the "pull-back" rod) compresses said spring during forward movement of the slide structure, thereby storing up energy for "snap" return on release of the structure. Some other pull-back means might of course be equally effectual.

One or more spring-projected plungers 66 formed in a part fixed to the table serve as shock-absorbing means for the slide structure on pull-back movement.

The aforesaid stop-bar embodies a T-shaped member having a roller 53^a on its lower end and is shown vertically movable in a block 67. This block is countersunk in the opening 59 in the table top and is slidably adjustable on the guide rails 62 for positioning the stop-bar according to the width of composite sections to be formed, i. e., with its abutment face in alignment (transversely of the table) with the forwardly extended ends of cleats stacked in the hoppers on opposite sides of the slide-platform. Under action of a "snap" spring 67^a within said block and pressing against a part on the lower end of the stop-bar, the latter is pushed and held normally down below the surface of the slide-platform.

On the under-carriage frame of the aforesaid slide structure, a cam-block 68 is shown adjustable according to positioning of the stop-bar for lifting the latter above the platform surface when the slide structure is moved forward to advance the push-member. Thus, the two plates are moved co-operatively for positioning and laterally compressing the slats between the cleat hoppers as hereinabove stated.

The slide structure is actuated intermittently by a cam-member 69 acting on a roller 70 journaled between the bars 60 of its under-carriage frame. This cam-member's movement is synchronized with that of the longitudinal conveyor so as to actuate the slide structure upon each delivery by said conveyor. It is shown keyed on a shaft 71 which is supported in bearings below the table top and driven by the main shaft 27 through a chain 72 passing over sprockets 73 and 74 respectively on the two shafts.

Said cam-member rotating with its shaft engages behind the aforesaid roller and thereby pushes the slide structure forwardly against resistance of its pull-back rod. During this movement, the delivered slats are positioned between the cleat hoppers by the aforesaid push-member advancing them against the stop-bar. At the limit of for-

ward movement, said roller rides over the leading edge of the cam-member and along the top thereof, holding the slide structure in advanced position with the slats compressed between said push-member and stop-bar for and during the cleating operation, whereupon the roller riding off the edge of the cam-member releases the slide structure for "snap" return by the pull-back rod.

The tiers of slats first subjected to the trimming and grooving operations are delivered successively by the conveyor between the cleat hoppers immediately following the cleating operation on a preceding tier, each tier in delivery pushing its preceding cleated tier forwardly and off the table.

As already indicated, hoppers for feeding cleats or splines forced into the grooved ends of the slats are opposingly arranged on opposite sides of the portion of slide-platform onto which the conveyor delivers (see Figs. 1 and 4).

According to this invention, a plurality of cleats are driven simultaneously from these hoppers directly into the receptive grooves at the different levels in both ends of the slats, so that a plurality-cleating of each tier or group is accomplished in a single passage through the machine. This is a marked improvement and advantage over the machine of the co-pending application wherein single cleats only can be applied at a time and double or more grooving of the slats leaves it nevertheless necessary to overturn and run them again through the cleating section or else to pass them onto an auxiliary machine for applying the additional cleats at different level in order to accomplish the same result. Without requiring any speed reduction, the invention thus provides for the complete formation of plural-cleated composite panels and therefore renders the machine capable of much higher output where such panels are to be sawed into several of single-cleating each.

The aforesaid hoppers each comprise adjacent rack-sections 75 and 76 which are adjustable laterally (by set screws and slotting) according to the length of cleats to be applied to the grooved slat tiers, and in which the cleats are stacked side-to-side upon one another. The first-mentioned and shorter of these sections accommodate single stacks of the cleats and discharge the same laterally in required plurality at a time into the receiving ends of the slats positioned therebetween as above described, while the last-mentioned and taller of the sections accommodate a plurality of stacks and feed the cleats longitudinally to the aforesaid discharging sections in number corresponding with the number discharged thereby so as to keep them fully supplied.

In the illustrative machine adapted to apply only two cleats to each (double grooved)

end of the slats, the feeding sections (76) accommodate two or double stacks of cleats for supplying the discharge sections (75) with two at a time on every expulsion of two in this instance from the latter. This is effected through discharge openings or slots in the sections, those of the feeding sections represented at 76^a (see Fig. 3) being located at the stack bottoms at offset levels slightly above the tops of the discharge sections, and those of the latter represented at 75^a being located at the levels of the grooves in the slats brought to position therebetween. Plates 77 on the fronts of these discharge sections (see Figs. 3 and 4) provide travel-ledges for the cleats expelled therefrom at levels above their bottom extreme and serve to prevent out-push of cleats intermediate the levels of expulsion.

20 The two sections of each hopper are connected by a bridge-member shown comprising a glue-receptacle 78 over which the cleats in successive pluralities are fed longitudinally from the taller to the shorter. Unless 25 glue-coating is to be dispensed with, the cleats in so feeding are passed between glue-applying rollers 79 and 80 journaled on said receptacle and the upper of which yields against spring 81. Said upper roller is 30 coated by drippings from a superposed glue-reservoir 82 through spout 83, while the lower is coated by rotation in a bath of the glue within the receptacle. A cold moisture-proof glue has been found preferable for the 35 purpose.

40 In the present arrangement, one of the feeding cleats is pushed to drop directly onto the stack in the discharge section, while the other is pushed to rest momentarily on the top edge thereof before dropping also onto said stack by a lateral push following its delivery as will hereinafter appear.

45 The glue-coated cleats stacked within the discharge sections of the hoppers are squeezed together by spring-tensioned tamps 84 for the purpose of spreading the glue therebetween so that each will acquire full coating on both sides. These tamps depend from span-bars 85 supported above the sections and lifted with each expulsion therefrom to permit replenishing cleats to feed thereto as already described. The lift of 50 said span-bars is effected by cam-elements 86 on reciprocating rods (to be mentioned later) acting thereunder against hold-down springs 87 on guides 88 therefor. Brackets 89 serve 55 as guides for the forward ends of the rods on which said cam-elements are carried. If preferred, the lifting means for these span-bars may be the same as employed for the 60 corresponding elements in the machine of the co-pending application.

65 As before indicated, a plurality of cleats (corresponding with the number of grooves cut in the slats), or two in this instance, are

expelled simultaneously from the discharge sections of the opposed hoppers and driven into the receptive end-grooves of the slat-tiers successively positioned therebetween. This is done by reciprocable pusher-members operating simultaneously in opposite directions.

70 These pusher-members (see Fig. 4) are carried by cross-heads 90 moving in transverse openings 91 through the table top on shafts 92, the latter being supported in brackets 92^a above the aforementioned shaft 71. Said cross-heads have cam-follower rollers 93 moving in oppositely grooved cam-members 94 which are slidably keyed on the shaft 71 and act against fixed cushion-blocks 94^a, thereby adapting them to simultaneous reciprocable movement in opposite directions with a pressure yield in approaching each other.

75 Affixed to these cross-heads are primary 85 push-plates 95 (in number corresponding with the number of cleats to be driven into the slats, being two in this instance) extending forwardly on the levels of the expulsion slots in the discharge sections of the hopper, so as coincidentally to engage behind the cleats at said levels and push them forcibly into the opposing grooves of the waiting slats, with movement of the cross-heads toward each other. Said plates are adjustable independently by slotting of the cross-heads to which affixture is advantageously effected by bolting; while a yield of their pressure in applying the cleats to the slats is afforded by springs 95^a working against a back-plate or bar. Tension on the cross-heads in "squeezing" 90 these push-plates against the slats is relieved by the aforesaid cushion-blocks (94^a) against which the actuating cam-members bear.

100 Supported by yokes 96 above said primary push-plates are secondary push-plates or bars 97 moving therewith and extending forwardly on the levels of the tops of the discharge sections of the hoppers. These secondary push-plates or bars serve to laterally 105 shove the cleats momentarily rested on the top edges of said sections in feeding thereto as previously described, so as to drop them onto the stacks therein. Like the primary push-plates, they are slotted for adjustment.

110 The yokes supporting said secondary push-plates also support parallel rods 98 which extend forwardly at both sides of the hopper discharge sections to slide in the aforementioned guide-brackets 89 and carry the cam-elements (86) for lifting the span-bars 85. These rods are longitudinally adjustable in the yokes by set-screws 99 so as to regulate the cam action, lifting said span-bars by under-riding the same with forward movement of the pusher-members and releasing them to drop again with backward movement of said members.

115 With the described movement of these pusher-members is synchronized the action of 120

elements for feeding the cleats from the feeding to the discharge sections of the hoppers. Said elements in this instance comprise push-bars 100 (see Figs. 1 and 3) working together in guide-ways under the stacks of the feeding sections to engage the ends of the lowermost cleats therein and push them out longitudinally across the bridge-member and between the glue-applying rollers to the discharge sections as already described.

These push-bars are reciprocated with the aforesaid pusher-members so as to feed the cleats in replenishing number as the pusher-members move on the expulsion and drive stroke, but travel faster in both directions than said pusher-members. This is accomplished by novel transmission of drive from the same shaft (71) that motivates the aforementioned cross-heads.

This transmission is effected through crank-arms 101 on projected ends of said shaft (71) imparting oscillatory movement to similar arms 102 (on opposite sides of the machine table) by connecting pitman-rods 103. These oscillated arms have slot-ways for adjustment of swing-arc or throw and carry segment gears 104 coaxing with small gears 105 to rotate separate shafts 106 alternately in opposite directions with forward and backward swing. Said shafts (106) are journaled in brackets transversely of the table and carry large gears 107 on their opposite ends. These large gears are engaged by rack-bars 108 to which they impart reciprocable movement with opposite rotations of their shafts. Said rack-bars extend longitudinally of the table abreast the aforesaid feeding sections and are held down to engagement with the gears by brackets 109 through which they move. On their forward ends they carry gears 110 working between other rack-bars 111 and 112 in parallel relation. The last-mentioned rack-bars are shown supported between the aforesaid brackets (109) and similar brackets 113 at the fronts of the feeding sections. The upper of these bars (111) are stationary while the lower (112) are reciprocably slideable in the supporting brackets and have lateral connection with the aforesaid push-bars 100 (under the feeding sections) for reciprocating the latter therewith. From the foregoing it will be understood that as the rack-bars 108 are actuated back and forth (with alternate rotations of shafts 106), the gears 110 thereon ratcheting against the upper rack-bars (111) impart accelerated movement in both directions to the lower rack-bars (112) and push-bars connected thereto, with the result that replenishing cleats will be fed to the discharge sections simultaneously with but slightly in advance of the expulsion therefrom on each "cleating" stroke of the cross-heads.

The illustrative machine is adapted to op-

erate as described on slats of different thicknesses required for different purposes. In making box-ends for example, slats of slightly more than standard thickness are preferably used, and the double grooving saws 70 forming double grooves in the ends thereof provide for the production of very strong composite sections with the forcing of cleats into these double grooves at both ends simultaneously. Such composite sections are allowed to discharge directly off the table into suitable receivers, or if they are to be sawed into two complete sections of single-cleating each, they are passed onto a slicing machine 75 adjusted to cut them longitudinally. If desired, obviously single-cleat sections may be formed by using only single grooving saws and single cleat-inserting push-plates.

In Fig. 4 the end of a double-grooved tier of slats is represented between the discharge 85 sections of the cleat hoppers, in position for cleats to be driven simultaneously into both grooves in opposite ends thereof. Slats with treble or more grooves may be cleated in the same way by a simple and obvious addition 90 of parts to so adapt the machine.

Thus the machine has a capacity and efficiency greatly exceeding the single-cleating machine of the co-pending application. Its gross output will be double that of the other 95 machine if double-cleated sections of slats are to be sawed into two, and triple that of the other machine if triple-cleated sections are to be sawed into three, and so on. Within reasonable limits, the gross output will 100 depend only on how many composite sections of single-cleating each are to be formed or cut from one plurality-cleated section or tier of slats passed through the machine.

The illustrative machine is also adapted 105 to adjustment for making composite sections of different lengths. For that purpose, the parallel ledge-rails 32 with associated hoppers and saws are co-operatively movable adjustably in maintained relation. This is accomplished through a two-way worm-shaft 114 shown journaled below and transversely of the table. The oppositely pitched worm-portions of this shaft work through hanger-bearings (not visible in the drawings) 115 extending upwardly through transverse grooves in the table top and fastened respectively to the ledge-rails on opposite sides of the table. Said shaft carries a hand-crank (not shown) on one end and rotation thereof is imparted to the aforementioned two-way worm-shaft 49 through a chain 115 passing over sprockets 114^a and 49^a respectively on the two shafts. An idling sprocket 116 advantageously serves for tightening this chain. The rotor-shafts of the grooving saw motors also extend through transverse slots in the table top and pass through apertured lug-portions 117 of the ledge-rails (see Fig. 3).

From the foregoing, it will be understood 130

that slight rotation of the shaft 114 communicated to the motor-moving shaft 49 will cause even lateral movement of the ledge-rails in opposite directions to desired space-
 5 ment, the slat-hopper, grooving saws and cleat-hopper with drive-transmission and gluing means on one side of the table being connected and movable with the ledge-rail on that side and the "push-over" levers, trim-
 10 saw, grooving saws and cleat-hopper with drive-transmission and gluing means on the other side of the table being connected and movable with the ledge-rail on said other side, so that all parts are moved cooperative-
 15 ly in maintained relation. The reason for mounting the trim-saw motor for movement transversely of the table is thus explained. As the parts are moved to variable adjustment in the manner stated, the bevel-gear
 20 30 is also moved along its shaft 26 in uninterrupted engagement with the gear 31 for maintaining the drive between said shaft and the shaft 20 of the transverse conveyor.

The machine as hereinbefore indicated is powered by an electric motor 29, which in this instance operates through a reduction gear 118 for driving the operable parts at appropriate speeds. A motor control switch is represented at 119 in Fig. 3.

30 An improved high-speed machine for making composite wooden sections or box-ends is thus provided. As various changes and modifications in construction with different combinations and sub-combinations of parts 35 may be made without departing from the scope of the invention, it is not intended to limit the same by the appended claims to the specific construction shown.

Having thus described my invention, what 40 I claim as new and desire to secure by Letters Patent of the United States is:—

1. A machine for making composite panels from odd lengths of lumber, comprising in combination, a table; a hopper on the table 45 in which lumber pieces are arranged side-by-side in loose tiers; an endless conveyor working below said hopper to successively remove and convey the tiers of pieces therefrom; a second endless conveyor working at substantially right angles to the first conveyor and onto which the former delivers; means for trimming the pieces to equal lengths and means for cutting a plurality of grooves therein at both ends while carried by the 50 second conveyor; a platform-portion onto which the last named conveyor delivers the pieces still in loose tiers; a push-element engaging behind the delivered pieces to move them forwardly on said platform-portion; a shifting stop-bar between which and said push-element the delivered pieces are temporarily held under lateral compression during a cleating operation; means cooperative-
 55 ly actuating said push and stop elements and holding the same with the pieces stationary

during the cleating operation; cleat-feeding hoppers arranged on opposite sides of said platform-portion where the pieces are held between the push and stop elements; means for driving a plurality of cleats from said hoppers and into the grooves at both ends of the pieces simultaneously as they are held under compression between the hoppers; and means feeding cleats into said hoppers coordinately with the discharge therefrom. 70

2. A machine according to the preceding claim, wherein the means driving the cleats from the opposed hoppers into the grooved pieces serves in part to feed the cleats thereinto. 75

3. A machine according to the first claim wherein the cleats feeding into the opposed hoppers are passed in relation to means applying a coating of glue thereto. 80

4. A machine according to the first claim, 85 wherein the cleat-driving means applies a plurality of the cleats into the receptive plurality of grooves in the pieces in a single operative stroke.

5. In a machine according to the first 90 claim, means bearing yieldingly upon the pieces to hold them down firmly while impelled along the table by the second conveyor comprising spring-like tamps angularly depending from bars supported over said conveyor's path of movement. 95

6. In a composite-panel-making machine, means assembling a number of wooden slats side-by-side in loose tiers; means trimming the slats to equal lengths; means forming a plurality of grooves in the ends thereof; and means applying a plurality of cleats simultaneously into said grooves. 100

7. In a composite-panel-making machine, means assembling a number of wooden slats side-by-side in loose tiers; means trimming the slats to equal lengths; means forming a plurality of grooves simultaneously in the ends thereof; means momentarily holding and laterally compressing the grooved slats of the tiers successively for a cleat-applying operation; and means applying a plurality of cleats simultaneously into said grooves. 105

8. In a machine of the character described, means for feeding cleats or splines in application to the grooved ends of slats comprising adjacent hopper-structures of different height in which the cleats are stacked and fed from one to the other, together with means for pushing a predetermined number of cleats from the bottoms of the two simultaneously, according to a predetermined cycle of operation, the cleats from the one being pushed to position for dropping into the other and the cleats from said other being forced (at different levels) directly into the grooved ends of the slats positioned receptively thereto. 110

9. In combination with cleat-feeding means according to the preceding claim, means for 115 120 125 130

5 applying a coating of glue to the cleats as they are pushed from the one hopper-structure to the other, said means embodying complementary rollers co-operably journaled between the structures and exposed to a bath of glue in position for applying a coating of the latter to the cleats passed successively therebetween.

10 10. Cleat-feeding means according to claim 8, wherein the means for simultaneously pushing a predetermined number of cleats from the bottom of the two hopper-structures have associated means operating to force the cleats discharged from the one to drop into the other for maintaining a full supply in 15 the latter.

11. In a machine of the character described, means for feeding cleats or splines in application to the grooved opposite ends of a group 20 or tier of slats, comprising opposing hopper-structures between which the slats are positioned and held under lateral compression, each of said structures embodying adjacent sections with the bottom of one level with the top of the other and in which the cleats are 25 stacked and fed from the one to the other across a bridging member, together with means for expelling a plurality of cleats from the bottoms of the two sections of both structures simultaneously according to a predetermined operative cycle, the cleats from the one 30 section of each structure being pushed to position for dropping into the other section and the cleats from said other section being forced at different levels directly into the 35 opposing grooved ends of the slats.

12. A machine for making composite panels from odd lengths of lumber, comprising in combination, a table; a hopper on the table 40 in which lumber pieces are arranged side-by-side in loose tiers; an endless conveyor working below said hopper to successively remove and convey the tiers of pieces therefrom; a second endless conveyor working at substantially right angles to the first conveyor 45 and onto which the former delivers; means for trimming the pieces to equal lengths and means for cutting a plurality of grooves therein at both ends while carried by the 50 second conveyor; a platform-portion onto which the last named conveyor delivers the pieces still in loose tiers; a push-element engaging behind the delivered pieces to move them forwardly on said platform-portion; a 55 shifting stop-bar between which and said push-element the delivered pieces are temporarily held under lateral compression during a cleating operation; means co-operatively actuating said push and stop elements and 60 holding the same with the pieces stationary during the cleating operation; cleat-feeding 65 hoppers arranged on opposite sides of said platform-portion where the pieces are held between the push and stop elements, said hoppers each comprising adjacent sections

with the bottom of one level with the top of the other and in which the cleats are stacked and fed from the one to the other across a bridging member; means for driving a plurality of the cleats at different levels from 70 said one section of each hopper simultaneously and directly into the grooves at both ends of the pieces as they are held under compression between said hoppers; and associated means for simultaneously feeding a corresponding number of the cleats from said 75 another to the aforesaid one section of each hopper to keep the latter full.

In testimony whereof I affix my signature.

HAROLD PITMAN SCHUCK.
